Patented Feb. 10, 1925.

UNITED STATES PATENT OFFICE.

WILLIAM VORDERWINKLER, OF ROSELLE, NEW JERSEY.

WINDING AND REELING DEVICE.

Original application filed May 11, 1922, Serial No. 560,025. Divided and this application filed March 3, 1923. Serial No. 622,465.

To all whom it may concern:

Be it known that I, WILLIAM VORDERWINKLER, a citizen of Austria, residing at Roselle, county of Union, and State of New Jersey, have invented certain new and useful Improvements in Winding and Reeling Devices, of which the following is a specification.

The principal object of this invention is to provide a new and improved device such as shown in my copending application, Serial No. 560,025, filed May 11th, 1922, of which this application is a division, for winding yarn, thread, etc., upon cone bobbins such as are commonly used for knitting machines, which device is simple in construction, composed of few parts, can be manufactured and sold at a low price and will not necessitate a high maintenance expense.

Another object is to provide a novel means for reciprocating the yarn or thread guiding means, and

Another object is to so construct the machine that the bobbin being wound will rest upon a stationary shaft and be rotated thereon by the frictional contact of a rotating driving member with its periphery.

For the accomplishment of these and such further objects as will hereinafter be apparent to those skilled in the art to which this appertains, the invention consists in the construction, combination and arrangement of parts herein specifically described and illustrated in the accompanying drawings, wherein is shown a preferred embodiment of the invention, but it is to be understood that changes, variations and modifications may be resorted to which fall within the scope of the claims hereunto appended.

In the drawings forming a portion of this disclosure—

Fig. 1 is a side elevation of a preferred embodiment of my invention.

Fig. 2 is a detail showing a front view of the driving means for the reciprocating thread guide.

Fig. 3 is a section on the line 3—3 of Fig. 2.

As shown in the drawings, a frame comprised of the uprights 10, and 11, lower braces 12, top pieces 13 and front bar 14, is provided. Mounted in journals 15 carried by the lower braces 12, is a main driving shaft 16, upon which is pivotally mount-

ed a swinging frame 17, provided at its upper end with a pair of spaced journals 18 in which is rotatably received a short shaft 19. Fixedly secured to the shaft 19 is a driving cone 20, a sheave pulley 21 being secured to the shaft 19 adjacent the upper bearing 18. A laterally projecting lug 22 integral with the frame is drilled to receive securely the headed stub shafts 23 upon which are rotatably mounted the idler 60 sheaves 24 over which and the sheave 21 is trained the belt 25, which passes over a driving sheave 26, secured upon the main shaft 16. A bracket 27 mounted on the front bar 14 is provided with an elongated 65 slot 28, through which the shaft 19 passes and serves as a guiding and limiting means for the swinging frame 17. A coil spring 28^a secured at its ends to an upright 11 and the swinging frame 17, normally holds 70 the frame in a rearward position, while the frame 17 is provided with a catch 28^b adapted to be engaged by the hooked end 29 of a pivoted lever 30 to hold the swinging frame 17 in a forward position with the 75 driving cone 20 in operative engagement with the bobbin 31, and a handle 17^a is secured to the frame 17 and extends forwardly to a convenient point to permit the operator to swing the frame forwardly into 80 85 operative position from the front of the machine.

A bracket 32 is secured to the front face of the front bar 14 and is provided with guide ways upon which is slidably received 90 the bobbin carriage 34, upon which is mounted a stationary bobbin spindle 35 which preferably is tapered as shown in the drawings to fit within the tapered hole of the bobbin 31. One side of the carriage is provided on its lower face with a series of ratchet teeth 38 adapted to be engaged by a pawl tooth 39, which projects upwardly from a lever 40, pivoted at one end as at 95 100 41, to the bracket 32 and terminating at its other end in a handle 42, a coiled spring 43 being provided between the lower face of the lever 40 and a laterally extending lug 44, to hold the pawl tooth 39 normally in engagement with the ratchet teeth 38. 105 Situated in a slot 45, at the rear end of the bracket 32, is an idler sheave 46, over which is passed a rope or wire 47, one end of which is secured to the bobbin carriage, and to the other end a weight 49. The pur- 110

pose of this weight is to force the bobbin carriage rearwardly and cause the bobbin to engage with the driving cone 20.

Mounted upon a forwardly extending bracket 50, secured to one of the uprights 10, is a small spindle 51, upon which is rotatably mounted a collar 52, the spindle preferably being provided with a shoulder to hold the collar spaced from the bracket. 5 A piece of wax 53 is rotatably received upon the spindle 51 and rests upon the collar 52, weights 54 being provided, if desired, to hold the wax downwardly upon the collar. 10 A small hooked wire 55 is secured to the bracket 50 and serves to guide the thread or yarn 56 from any suitable supply, such as indicated by the numeral 57, to the wax applying device, the yarn being passed between the upper face of the collar 52 and 15 the under face of the wax 53. The hook 55 is located to one side of the axis of the spindle 51, while upon the other side of said spindle at a point substantially diametrically opposite of the hook 55, is a second guiding hook 55', which extends downwardly to one side of the inner face of the bracket 50 and is pivoted as at 58 to one end of a small counterbalancing lever 59. The lever 59 is pivoted as at 60, to the 20 lever 30, and when the yarn 56 is passed through the hook 57, in its passage from the hook 55 to the reciprocating thread guide 61, it is engaged under the hook 55' holding the counterbalancing lever 59 in 25 the position shown in Fig. 1. Should the yarn supply become exhausted or should the thread break it would be evident that the tension in the yarn being released, the lever 59 would drop upon and cause the lever 30 to swing upon its pivot thus releasing the hook 29 and permitting the spring 28^a to move the swinging frame 17 rearwardly and release the driving cone 20 from engagement with the bobbin 31, it being understood 30 that the pawl 37 being in engagement with the ratchet teeth 38 will prevent the bobbin from following the driving cone. 35

Means are also provided for releasing the driving engagement of the driving cone 50 and bobbin when the amount of yarn wound upon the bobbin reaches a predetermined diameter and comprises a downwardly projecting lug 30' upon the lever 30 located in alignment with the weight 49. When 55 the carriage 34 is moved outwardly by the increasing diameter of the yarn wound upon the bobbin, the weight 49 will move upwardly, as will be obvious, until the upper face of the weight reaches the lug 30', thus 60 swinging the lever 30 and releasing the hook 29.

The thread or yarn guiding hook 61 is formed upon the end of a small metal rod 62, which is slidably and adjustably received in one end of pivoted lever 63, which is

adjustably secured to a transverse shaft 64, rotatably mounted in journal brackets secured to the uprights 11. Secured adjacent one end of the shaft 64 is a crank lever 65 to which is secured the upper end of a reciprocating rod 66 slidably mounted in the brackets 67. The lower end of the rod 66 is secured to a plate 70 having a guide rod 72 slidably mounted in brackets 67. A crank disc 73 is secured upon a short jack shaft 71, suitably journalled on one of the uprights 11 and secured to the jack shaft is a belt pulley 74, a belt 75 being trained around the pulley 74 and a driving pulley 76 secured to the main shaft 16. The pulleys 74 and 76 are so proportioned as to produce about three revolutions of the bobbin to one complete reciprocation of the thread guiding hook 61.

The operation of the device is as follows, 85 assuming the parts are in the position shown in Fig. 1, the swinging frame 17 being held in its forward position the driving cone 20 is in engagement with the bobbin 31, the bobbin being held in frictional engagement 90 with the cone by the weight 49. The rotation of the bobbin winds the yarn 56 thereon and the reciprocation of the guiding hook 61 guides the yarn and causes it to be distributed uniformly and evenly upon 95 the bobbin. In order to insure the proper winding of the bobbin, quick return movements at the ends of the stroke of the guiding hook, are essential, as well as uniform speed at the intermediate points. As the 100 size of the bobbin increases the bobbin carriage 34 will move outwardly, the pawl tooth 39 being depressed at intervals by the ratchet teeth 38 and moving downwardly against the action of the spring 43. When 105 the weight 49 engages the lug 62, the hook 29 will be released from the catch 28^b and the swinging frame will move inwardly under the action of the spring 28^a releasing 110 the driving engagement of the cone 20 and bobbin, it being understood that the engagement of the pawl and ratchet will prevent the bobbin from following the cone. Should 115 the yarn supply 57 become exhausted or the yarn thread 56 break, the release of the tension in the yarn will permit the counterbalancing lever 59 to drop and release the hook 29. After placing an empty bobbin upon the spindle 35, the operator grasps the handle 17^a and pulls the frame 17 forwardly until the hook 29 is engaged, the 120 yarn thread is threaded through the hooks 55, 57 and 61 and between the wax 53 and collar 52, a few turns of the yarn is wound around the bobbin, and the handle 42 is depressed releasing the pawl and ratchet 125 and allowing the bobbin to move forwardly into driving relation with the cone 20.

In Figs. 2 and 3, a modified form of cam means for reciprocating the thread guiding 130

hook 61 is shown and crank disc 73 provided with a roller 68 which projects into a cam groove 80 defined by the inner wall of a substantially figure 8 shaped recess formed in 5 the face of the cam plate 70, and a pair of pivoted plates 81. One of each of these pair of plates is pivotally secured as by the headed screw 82 centrally of each lobe of the 10 8 shaped recess and each plate is provided with a tail portion 83 which is normally held in engagement with the wall of the recess to project across the cam groove 80 by a bent spring 84 one end of which engages a small pin 85 projecting outwardly from the 15 plate 81, while the other end is bent inwardly and is suitably secured in the screw 82. The operation of this cam member is as follows: Assuming that the disc 73 is rotating in the direction of the arrow in Fig. 20 2, the roller 68 is shown approaching the tail portion 83 of the right hand plate, the continued rotation of the crank disc will cause the roller 68 to move the plate 81 against the action of the spring 84 upon its 25 pivot 82, forcing the plate 81 to rotate upon the cam plate 70, in a counter clockwise direction. The tail 83 will move across the cam groove and will block the central portion of the groove compelling the roller 68 30 to pass upwardly and across into the other lobe of the figure eight groove, it being understood that the spring 84 being placed under tension will tend to increase the acceleration produced at this point by the 35 shape of the cam groove.

While the thread guiding hook 61 is shown as pivotally mounted and having an oscillating motion, it will be obvious that it could be mounted for a straight reciprocating motion and as the term reciprocating would also include an oscillating motion, I prefer to use the term reciprocating as referring to the motion of the hook 61.

Having thus described my invention, what 45 I claim as new and desire to secure by Letters Patent, is:

A bobbin winder comprising a frame, a bobbin spindle rotatably mounted on said frame, frictional means to drive a bobbin disposed on said spindle, means to feed a thread under tension to the bobbin including a reciprocating thread guide and means to reciprocate said thread guide comprising an actuating rod slidably mounted on said frame, cam actuated means to reciprocate said rod comprising a grooved cam connected with said rod, a crank disc provided with a cam roller to engage within the cam groove, and means to rotate said disc.

60 2. A bobbin winder comprising a frame, a bobbin spindle rotatably mounted on said

frame, means to drive a bobbin disposed on said spindle, means to feed a thread under tension of the bobbin including a reciprocating thread guide and means to reciprocate said thread guide comprising an actuating rod slidably mounted on said frame, and cam means to reciprocate said rod comprising a plate provided with a substantially figure 8 shaped recess, a plate pivoted at the 65 centres of each of the lobes of said recess, said plate and recess defining a cam groove constructed and arranged to secure a uniform motion of said thread guide at points intermediate the ends of its reciprocation 70 and an accelerated motion at the ends of its reciprocation.

3. A bobbin winder comprising a frame, a bobbin spindle rotatably mounted on said frame, means to drive a bobbin mounted on said spindle, means to feed a thread under tension to said bobbin including a reciprocating thread guide and means to reciprocate said thread guide comprising an actuating rod slidably mounted on said frame, cam means to reciprocate said rod comprising a plate provided with a substantially figure 8 shaped recess, and a plate pivoted at the 80 centres of each of the lobes of said recess, said plate and recess defining a cam groove, 85 said plate being provided with a tail portion, spring means to normally hold said tail portion across said cam groove, said cam roller being adapted to engage said tail portions at points corresponding to the ends 90 of the reciprocating motions of the thread guide and move said tail portions out of said groove against the action of said spring means.

4. A bobbin winder comprising a frame, 100 a bobbin spindle rotatably mounted on said frame, means to drive a bobbin disposed on said spindle, means to feed a thread under tension to the bobbin including a reciprocating thread guide and means to reciprocate said thread guide comprising an actuating rod slidably mounted on said frame, cam means to reciprocate said rod comprising a recessed plate, and means pivoted within and defining with said recess, a cam groove constructed and arranged to provide an uniform motion of said thread guide at points intermediate the ends of its reciprocating motion and an accelerated 105 quick return at the ends of said motion, and spring means to cause said pivoted means to assist said accelerated quick return motions.

In testimony whereof I have affixed my signature.

WILLIAM VORDERWINKLER.
